US00D551198S

(12) United States Design Patent (10) Patent No.: US D551,198 S
(45) Date of Patent: * Sep. 18, 2007

(54) DIGITAL VIDEO RECORDER

(75) Inventor: Jin-Wook Kim, Seoul (KR)

(73) Assignee: Samsung Electronics Co., Ltd., Kyunggi-do (KR)

() Term: 14 Years

(21) Appl. No.: 29/259,105

(22) Filed: May 2, 2006

(51) LOC (8) Cl. 14-01

(52) U.S. Cl. D14/136

(58) Field of Classification Search D14/135–136,
D14/156–157, 167–168, 197–198, 188, 357,

(57) CLAIM

The ornamental design for a digital video recorder, as shown and described.

DESCRIPTION

FIG. 1 is a top front perspective view of a digital video recorder showing my new design;

FIG. 2 is a front elevational view thereof;

FIG. 3 is a rear elevational view thereof;

FIG. 4 is a left side elevational view, the right side being symmetrical thereof;

FIG. 5 is a top plan view thereof; and,

FIG. 6 is a bottom plan view thereof.

1 Claim, 4 Drawing Sheets
